BOAT FOR MOTORCYCLE OR THE LIKE

Robert S. Caferelli, 220 Civic Center Drive,
North Las Vegas, Nev. 89030

Filed Mar. 6, 1975, Ser. No. 555,984

Term of patent 14 years

Int. Cl. D12—96

U.S. Cl. D12—62

Fig. 1.

Fig. 2.

Fig. 3.

Fig. 4.

*Fig. 5.**Fig. 6.*

FIG. 1 is a perspective view of a boat for motorcycle or the like showing my new design;

FIG. 2 is a side elevational view of the boat shown in FIG. 1;

FIG. 3 is a top plan view of the boat shown in FIG. 2;

FIG. 4 is a bottom plan view of the boat shown in FIG. 2;

FIG. 5 is a front end elevational view of the boat shown in FIG. 2; and

FIG. 6 is a rear end elevational view of the boat shown in FIG. 2.

I claim:

The ornamental design for a boat for motorcycle or the like, as shown and described.
